UNITED STATES PATENT OFFICE.

ALONZO KIMBALL MARSH, OF NEW YORK, N. Y., ASSIGNOR TO A KIMBALL COMPANY, OF NEW YORK, N. Y., A CORPORATION OF NEW YORK.

MARKING TICKET.

Application filed October 7, 1922. Serial No. 593,037.

To all whom it may concern:

Be it known that I, ALONZO KIMBALL MARSH, a citizen of the United States, and resident of New York, county of New York, and State of New York, have invented an Improvement in Marking Tickets, of which the following description, in connection with the accompanying drawing, is a specification, like characters on the drawing representing

10 like parts.

This invention has for its object the provision of a marking ticket which can be readily and firmly secured in position on an article to be marked which article is of a character that would be injured by being penetrated by pins or left in contact with metal. Articles such as handkerchiefs, laces, and fine fabrics may be injured by the use of pins and other metal fasteners commonly employed in connection with marking tickets. Such pins or fasteners, unless made with exceeding care, may catch the fine fibres or threads forming the fabric and injure or damage the fabric. So also the contact of 25 a metal fastener with such an article or fabric may, if any dampness be present, result in a stain due to rust.

The object of this invention is, therefore, to provide a marking ticket which can 30 neither by catching on the fibres or threads or by staining the fabric injure fine and expensive articles.

The object of the invention is to provide such a marking ticket which clasps or grips 35 the article or fabric to be marked so as to prevent accidental removal of the marking ticket and insures the correct marking of the article or fabric in an inexpensive and efficient manner.

40 These and other objects and features of the invention will appear more fully from the accompanying description and drawings and will be particularly pointed out in the claims.

45 In the drawings:

Fig. 1 is a plan view showing the corner of an article such as a handkerchief with a marking ticket embodying a preferred form of the invention placed thereon in the first 50 step of its attachment thereto;

Fig. 2 is a view similar to Fig. 1 illustrating the second step in the attachment of the marking ticket;

Fig. 3 is a view similar to Fig. 1 illus-

trating the final position of the marking 55 ticket on the article;

Fig. 4 is an enlarged view in vertical cross section of the construction shown in Fig. 1;

Fig. 5 is an enlarged view in vertical cross 60 section of the construction shown in Fig. 3;

Fig. 6 is a view in transverse cross section taken on the line 6—6 of Fig. 1;

Fig. 7 is a plan view of the marking ticket shown in the other figures, including a slight 65 modification.

In the marking of fine and delicate articles and fabrics such as handkerchiefs and laces etc. it has been common heretofore to use gummed labels and other devices to prevent 70 injury or damage to the article or fabric because of the danger from injury which may occur when pin tickets are employed. If the pin of a pin ticket catches the fibres or threads of which such articles are composed 75 the damage which may be produced is very great and the same is true if the article is stained by rust from the pin or fastening device.

This invention provides a simple, efficient 80 and inexpensive marking ticket which may readily and quickly be secured to an article or fabric of the finest quality and most delicate character without any danger of injury or damage and which may as quickly 85 be removed therefrom.

The marking ticket of this invention is capable, therefore, of a wide application of use whenever it is desired to mark with suitable indicia such as price, size, style etc. a 90 valuable and delicate article. The marking ticket of this invention is of the general type disclosed in the patent to Wallin #1,073,828 of September 23, 1913.

The marking ticket comprises essentially 95 a card of flexible non-metallic material such as heavy paper or thin cardboard preferably of two or more plies glued or cemented together.

The surface of the card affords ample 100 space for the desired indicia.

In addition the marking ticket comprises essentially a division of the card into at least three sections by transverse scores and the provision of a soft wire stiffener or stiffeners 105 extending longitudinally of the card across the scores. In a preferred form of the invention such as illustrated the card is of rec-

tangular shape made up of two plies 1 and 2 of material between which is interposed the soft wire stiffener or stiffeners. This card is divided by the transverse scores 3 and 4 into three sections 5, 6 and 7. The soft wire stiffener 8 in the first six figures of the drawing is shown as extending longitudinally near one edge of the card and throughout the entire length of the card 5 but the essential feature is that it extends across both scores 3 and 4. In Figure 7 there are two of the soft wire stiffeners located at the positions 9 and 10 and extending longitudinally of the card across the 10 scores one adjacent each edge of the card. These soft wire stiffeners enable the card when bent upon either score 3 or 4 to retain its bent condition firmly and insure the proper clamping of the material. 15 The section 6 of the card between the scores 3 and 4 is provided with means for engaging the material to be marked. A simple and effective means for this purpose is produced by striking or punching out of 20 the section 6 a tongue 11. If now the edge or a corner of an article such as a handkerchief 12 be inserted between this tongue 11 and the body of the card as shown in Figure 1 it will be engaged and held between 25 the tongue and the body of the card but this engagement is only a preliminary one as it is not sufficient to hold the marking ticket firmly in place. 30

In attaching the marking ticket after the 35 article to be marked has been engaged with the central section 6, as by the tongue 11, the adjoining section such as the section 6 of the card is bent back on the score 8 intermediate between the section 6 and the section 5 against the central section 6 as shown in Figure 2 and then these two sections 5 and 6, thus clamped together over the article to be marked, such as the handkerchief 12, are bent back on the score 4 against the 40 45 third section 7 or into the position shown in Figure 3. When in this position the marking ticket is firmly clasped to the article because the soft wire stiffener or stiffeners retain the marking ticket in the bent and 50 clamped position.

The front surface of the section 7 is particularly adapted, as illustrated, for receiving the marking indicia but in addition if desired a portion of the surface of the section 6 may be employed.

It will thus be seen that there is no metal whatever in contact with the article to be marked and there is no penetration by pins or otherwise of the article.

60 When it is desired to remove the marking ticket it is simply necessary to unbend the sections of the marking ticket and withdraw the article.

The size of the card and the shape may vary as required and any suitable soft wire 65 such as employed in this type of ticket and which retains a permanent set when it is bent or doubled back upon itself may be employed.

Having thus described my invention, 70 what I claim as new and desire to secure by Letters Patents, is:

1. A marking ticket comprising a card divided by two transverse scores into three sections, means on the central section for 75 engaging the material to be marked, and a soft wire stiffener extending longitudinally of the card across the scores whereby the ticket may be secured to the material to be marked by engaging the material with the central section, bending an adjoining section on the intermediate score back against the central section, and then bending these two sections and the engaged material on the other score back against the third section. 80 85

2. A marking ticket comprising the construction defined in claim 1 in which there are two of the soft wire stiffeners, one adjacent each longitudinal edge of the card and each extending across the scores. 90

3. A marking ticket comprising a card divided by two transverse scores into three sections, a tongue struck out of the central section, and a soft wire stiffener extending longitudinally of the card across the scores 95 whereby the ticket may be secured to the material to be marked by placing the material between the tongue and the body of the central section, bending an adjoining section on the intermediate score back against the central section, and then bending these two sections and the interposed material on the other score back against the third section. 100

4. A marking ticket comprising a two ply card divided by two transverse scores into three sections, a tongue struck out of the central section, and a soft wire stiffener interposed between the plies and extending longitudinally of the card across the scores whereby the ticket may be secured to the material to be marked by placing the material between the tongue and the body of the central section, bending the section adjacent the base of the tongue on the intermediate score back against the central section, and then bending these two sections and the interposed material on the other score back against the third section. 105 110 115

5. A marking ticket comprising the construction defined in claim 4 in which there are two of the soft wire stiffeners one adjacent each longitudinal edge of the card and each extending across the scores. 120

In testimony whereof, I have signed my name to this specification.

ALONZO KIMBALL MARSH.
